UNITED STATES PATENT OFFICE.

GUSTAVE F. KOLB, OF MOUNT VERNON, NEW YORK.

DESIGN FOR A BIRTH-SPOON.

42,630.

Specification for Design.

Patented June 18, 1912.

Application filed November 29, 1909. Serial No. 530,521. Term of patent 3½ years.

To all whom it may concern:

Be it known that I, GUSTAVE F. KOLB, a citizen of the United States, residing at Mount Vernon, in the county of Westchester, State of New York, have invented a new, original, and ornamental Design for Birth-Spoons, of which the following is a specification, reference being had to the accompanying drawings, forming a part hereof.

In these drawings, Figure 1 is a front view of the spoon showing my new design, and Fig. 2 is a rear view thereof.

I claim:

The ornamental design for a birth spoon, as shown.

GUSTAVE F. KOLB.

Witnesses:

JOSEPH J. FISCHER,
FRED H. BOWERSOCK.
